UNITED STATES PATENT OFFICE

JOHN SINKO, OF CHICAGO, ILLINOIS

PROCESS OF MAKING METALLIC CONTAINERS

Application filed December 13, 1929. Serial No. 413,731.

This invention relates to metallic containers and to a process for making the same. In the particular form illustrated herewith, the container is a barrel-shaped receptacle adapted for use as a bank. The invention is not limited to this particular construction, however, as it might be applied to other receptacles and to receptacles for other purposes.

One object of the invention is to provide 10 a receptacle and the process for making it, in which the receptacle itself and a cover retaining flange of the receptacle are made in a single piece and preferably as part of a continuous step-by-step process.

15 Other objects will appear from time to time in the specification and claims.

My invention is illustrated more or less diagrammatically in the accompanying drawings, wherein

20 Fig. 1 is a transverse, cross section, showing the receptacle in one stage of the manufacture.

Fig. 2 is a similar view, showing the receptacle as further processed.

25 Fig. 3 is a similar view, showing the receptacle in its final form.

Like parts are designated by like characters throughout the figures.

The receptacle is designated generally by 30 the letter A. As shown, it is flared at its sides as at A¹ into the general shape of a barrel. It is provided preferably with laterally extended portions A² which simulate in appearance the hoops of a barrel. The closed 35 end of the receptacle may be indented, as indicated generally at A³.

The receptacle, in its general form, may be made in the manner described in Patent No. 1,647,547, or it may be produced in any 40 other suitable way.

The receptacle is, however, always to be made of a single blank. This blank will normally be flat to begin with and usually circular in outline. A generally hollow or cup-shaped 45 form will be given to it and it may or may not be given the outer bulged barrel shape, as indicated in Fig. 1. Whatever form it takes and however it is made, there will be left an upwardly extending part which extends 50 upwardly beyond a point which, in the fin-

ished receptacle, will define the top of the receptacle. It is one of the important features of the present invention to deal with this upward extension and to form from it the termination of the upper end of the receptacle about its open mouth and also to form from it a flange adapted to position and to be used to seat and to fasten, a closure in the open end of the receptacle.

As shown in Figure 1, the process of manufacture has been partially completed so that the barrel with its hoops and indented bottom has been formed. A portion of the blank from which the barrel was originally drawn is left extending upwardly as designated by 60 the letter B, as shown in Fig. 1. In the ordinary manufacturing process the upper edge of this portion B will be rough and uneven and as shown in Fig. 1 it has been smoothed or trimmed so as to provide an even upper 65 edge.

As shown in Fig. 2 the next step in completing the form shown in Fig. 1 has been taken. The upwardly extending part B has been partially pressed inwardly to produce 70 the inwardly extending shoulder B¹ and beyond this shoulder B¹ the upper edge portion has been upwardly pressed again as at B².

As shown in Fig. 3, the manufacturing process has been completed. The upwardly 75 extending edge portion B² has been struck downwardly. As this takes place, bending occurs generally in the shoulder B¹ with the result that almost the entire part B² is displaced downwardly and finally assumes the 80 position of an inwardly extending flange. In this operation the material generally designated as the shoulder B¹ is stretched and bent and the portion B² of Fig. 2 is deformed 85 as it is forced downwardly so that the relatively narrow flange B³ remains extending inwardly. Any suitable closure may then be seated in the open end. It may rest on the flange B³ and may engage the under side of 90 the flange so as to be held in engagement 95 within the open end of the receptacle to prevent accidental or unauthorized displacement or removal.

Although I have shown an operative device 100 and a successful process for making the same,

it will be obvious that many changes in the size and arrangement of the parts and in the details of the process of making the device might be developed without departing 5 from the spirit of my invention.

I claim:

1. A process of forming a unitary receptacle which includes the following steps: shaping a single blank to provide a hollow member 10 having an open top and provided with an upward extension, pressing inwardly a portion of said upward extension, whereby there are formed an inwardly extending shoulder and an upwardly extending portion, and 15 subsequently exerting a pressure on said upward extension, forcing the same downwardly to provide an inwardly facing, annular flange positioned below said shoulder.
2. A process of forming a unitary receptacle which includes the following steps: shaping a single blank to provide a hollow member having an open top and provided with an upward extension of lesser diameter than the major portion of the main body, pressing 20 inwardly a portion of said upward extension, whereby there are formed an inwardly extending shoulder and an upwardly extending portion, and subsequently exerting a pressure on said upward extension, forcing the same 25 downwardly to provide an inwardly facing, annular flange positioned below said shoulder.
3. A process of forming a unitary receptacle which includes the following steps: shaping a single blank to provide a hollow member having an open top and provided with an upward extension, pressing inwardly a portion of said upward extension, whereby there are formed an inwardly extending shoulder 30 and an upwardly extending portion, of less diameter and shorter than said first mentioned upward extension, and subsequently exerting a pressure on said reduced upward extension, forcing the same downwardly to 35 provide an inwardly facing, annular flange positioned below said shoulder.

4. A process of forming a unitary receptacle which includes the following steps: shaping a single blank to provide a hollow member 40 having an open top and provided with an upward extension, pressing inwardly a portion of said upward extension, whereby there are formed an inwardly extending shoulder and an upwardly extending portion 45 of less diameter and shorter than said first mentioned upward extension, and subsequently exerting a pressure on said reduced upward extension, forcing the same downwardly to provide an inwardly facing, annular flange positioned below said shoulder.
5. A process of forming a unitary receptacle which includes the following steps: shaping a single blank to provide a hollow 50

member having an open top and provided with an upward extension of lesser diameter than the major portion of the main body, pressing inwardly a portion of said upward extension, whereby there are formed an inwardly extending shoulder and simultaneously an upwardly extending portion of less diameter and shorter than said first mentioned upward extension, and subsequently exerting a pressure on said reduced upward extension, forcing the same downwardly to provide an inwardly facing, annular flange, positioned below said shoulder and having the same general diameter as the said reduced upwardly extending portion. 70

6. The process of forming a complete unitary receptacle, which includes forming a single blank into a hollow, open ended member having an upwardly extending portion, treating said upwardly extending portion to force a part intermediate its ends inwardly to form an inwardly extending shoulder and retaining a portion of said upwardly extending part in the upwardly extended position, subsequently exerting pressure upon said upwardly extending portion to force the same downwardly and to form it into an inwardly extended, annular flange within said receptacle. 75

7. The process of forming a complete unitary receptacle, which includes forming a single blank into a hollow, open ended member having an upwardly extending portion, treating said upwardly extending portion to force a part intermediate its ends inwardly to form an inwardly extending shoulder and retaining a portion of said upwardly extending part in the upwardly extended position, and causing it to remain as an upwardly extending portion of reduced diameter and 90 length, subsequently exerting pressure upon said upwardly extending portion to force the same downwardly and to form it into an inwardly extended, annular flange within said receptacle. 95

8. The process of forming a complete unitary receptacle, which includes forming a single blank into a hollow, open ended member having an upwardly extending portion, treating said upwardly extending portion to force a part intermediate its ends inwardly to form an inwardly extending shoulder and retaining a portion of said upwardly extending part in the upwardly extended position, subsequently exerting pressure upon said upwardly extending portion to force the same downwardly below the said shoulder and to form it into an inwardly extended, annular flange within said receptacle. 100

9. The process of forming a complete unitary receptacle, which includes forming a single blank into a hollow, open ended member having an upwardly extending portion, treating said upwardly extending portion to force a part intermediate its ends inwardly 115

- 120
- 125
- 130

to form an inwardly extending shoulder and retaining a portion of said upwardly extending part in the upwardly extended position, and causing it to remain as an upwardly extending portion of reduced diameter and 5 length, subsequently exerting pressure upon said reduced upwardly extending portion to force the same downwardly below the said shoulder and to form it into an inwardly extended, annular flange within said receptacle.

Signed at Chicago, county of Cook and State of Illinois, this 11th day of December, 1929.

JOHN SINKO.
